UNITED STATES PATENT OFFICE.

RICHARD R. EZDORF, OF BALTIMORE, MARYLAND, ASSIGNOR TO FUELO CORPORATION, OF WASHINGTON, DISTRICT OF COLUMBIA, A CORPORATION OF DELAWARE.

OIL BURNER.

Application filed August 19, 1926. Serial No. 130,310.

This invention relates to oil burners.

The primary object of the invention is to provide an oil burner with instrumentalities for delaying the admission of oil to the discharging device until after a predetermined condition exists within the fan housing.

A further object of the invention is to provide means for regulating the supply of oil to the discharging and atomizing device until after the motor has started and until a predetermined pressure condition exists within the fan housing.

A further object of the invention is to provide an automatic means for decreasing or shutting off entirely the oil feed when the pressure within the fan housing recedes below its normal operating condition. More specifically, the invention comprehends the employment of a diaphragm within a chamber, which chamber is in communication with the fan housing and to connect the diaphragm with a valve actuating device whereby the valve will be actuated to admit oil to the nozzle only after a predetermined pressure condition is maintained within the said diaphragm chamber.

Still another object of the invention is to provide an adjustable means between the diaphragm and the valve actuating device whereby the admission of oil to the atomizing device can be regulated in accordance with the needs of the occasion. Still another object of the invention is to provide an oil feeding device snugly located within the confines of the rotating cup atomizer for the purpose of feeding the oil as a film to the periphery of the rotating cup, at which point the oil is subjected to an air blast for complete atomization.

Other objects of the invention will be apparent to those skilled in the art upon a reading of the following specification in conjunction with the drawings attached hereto and forming a part hereof, in which

Fig. 1 is a top view showing the complete assembled machine,

Fig. 2 is a longitudinal section taken on lines 2—2 of Fig. 1,

Fig. 3 is a detailed view taken on lines 3—3 of Fig. 3,

Fig. 4 is a detailed view showing the different angular positions of the alternate long and short vanes,

Fig. 5 is a view partly in section showing

the arrangement of the oil feeding pipes and 55 the pivotally arranged air shutters for regulating the supply of air to the fan housing,

Fig. 6 is a detailed longitudinal sectional view of the stationary oil receiving device and the rotatable cup and oil feeding device, 60 and

Figs. 7 and 8 are detailed views of the oil feeding device and the oil receiving device, respectively.

Referring now to the drawings, reference 65 numeral 1 designates an enclosure for the motor 2. At the rear of the housing, there is preferably provided a screen 3 for the admission of air for cooling the motor and preheating the air preliminarily to the introduction of the air to the outlet of the apparatus where it contacts with and atomizes the discharging oil. 4 designates a motor base provided with a diaphragm chamber 5; suitable fastening bolts 6 are provided for 70 securing the motor to the base. Within the confines of the diaphragm chamber 5 there is positioned a diaphragm 7. A downwardly extending rod is secured at its upper end to the diaphragm and extends through the 75 opening 9 provided within the wall 10 of the chamber 5. This rod is provided with a series of openings 11 at its lower end in which openings one end of the lever 12 may be adjustably secured for the purpose hereinafter described. The rod 12 is pivotally mounted as at 13 and is provided with an engaging portion 14 for lifting the device 15 upwardly to thereby open the valve 16 when the pressure within the chamber 5 is sufficient to distend the diaphragm and rock the lever 12 downwardly. The fan housing 17 is secured to the base 4 by means of devices 18. This fan housing has secured thereto a stationary flange 18 and an outlet 90 nozzle 19. A circumferential opening 20 is provided for the fan housing to receive air which has been preheated by passing over the motor 2. The housing 1 is preferably supported by a laterally extending circumferentially disposed flange 21, there preferably being a packing 22 interposed between the periphery of the housing 1 and the aforesaid flange 21. 23 is a rotatable hub secured to the motor shaft 24 by means of a screw 100 25. This screw 25 furthermore secures the atomizing cup 26 fast to the shaft 24 to thereby rotate the cup when the motor is in

operation. Within the confines of the atomizing cup 26 there is provided an oil feeding device 27 provided with spirally arranged grooves 28 for the purpose of positively feeding the oil outwardly as a film to the periphery of the atomizing cup. The hub 23 has secured thereto the fan 27', the said fan comprising walls 28' and 29'. Interposed between the walls of the fan are vanes 30' and 31'. These vanes are positioned at varying angles and are of alternative lengths, as shown in Fig. 4.

Stationarily disposed upon the motor extension 29 and non-rotatably associated with the motor shaft 24 there is provided an oil receiving device 30 secured to the aforesaid flange 29 by means of a screw 31. This oil receiving device is provided with an aperture 32 for receiving the oil conduit 33. The aperture 32 has communicating therewith an obliquely disposed port 34. Upon the interior of the oil receiving device 30 there is provided a tubular element 35 fitting over the motor shaft 24 and provided with a circumferential recess 36 in connection with the aforesaid port 34. This circumferential recess has communicating therewith, preferably at the top, a multiplicity of restricted longitudinal ports 37 for discharging the oil from the circumferential recess 36 with considerable velocity into the inner portion of the rotatable cup 26 from whence the oil is positively fed outwardly by the rotating device 27 having the spiral grooves therein as hereinbefore described.

The oil for the burner is supplied in any well-known and desirable manner, but I preferably employ an overhead auxiliary receptacle having associated therewith an automatic pump for maintaining the requisite supply of oil for the demands of the burner. Under head pressure, the oil is supplied by means of a pipe 38 through the valve casing 39 within which is secured the aforesaid valve 16, and from thence the oil is fed through a pipe 40 upwardly through the communicating conduit 41 and thence laterally as at 42 where it is connected to the aperture 32 as above described. A manually operable valve 43 is provided for completely shutting off the oil supply when desired.

The means of communication between the fan chamber and the diaphragm chamber may be provided in any desirable manner but preferably by means of the conduit 44.

The operation of the burner may be briefly described as follows:

The motor 1 is first placed into operation, and the rotation of the motor shaft 24 causes a corresponding rotation of the hub 23 and the fan 21'. When a sufficient amount of pressure is built up within the fan housing 17, this pressure is transmitted to the chamber 5 and causes a downward distension of

the diaphragm 7, which diaphragm, through the associated devices, 8, 12, 14, and 15 open the valve 16, thus permitting oil to be supplied through the oblique passage 34 and the ports 37 into the cup 26 from which it is positively fed outwardly by means of the oil feeding device 29. It will thus be seen that the oil is not admitted until after a time interval has expired and until after a predetermined pressure condition exists within the fan chamber, this obviating the dangers incident to accumulating oil during the starting operation and the smoking and carbonization incident thereto. Moreover, when the pressure within the fan chamber recedes below that of normal operating conditions, the oil supply is immediately and automatically shut off to prevent a further admission of oil to the chamber. The oil is furthermore automatically and proportionately controlled by virtue of the aforesaid diaphragm. The term "diaphragm" as used in my claims is intended to embrace pumping devices such as pistons which may be devised to operate in a manner similar to my invention. Pivotally arranged air shutters 45 are provided whereby the air to the fan housing 17 may be regulated as desired.

It will be understood that various changes in the arrangement and construction of parts of my apparatus may be made without departing from the spirit of the invention as expressed in the following claims.

Having thus described the invention what I claim is:

1. In an oil burner, in combination, a fan housing, having a rotatable fan therein, an oil discharging cup within the fan housing, said cup and fan being operatively connected with the shaft of an electric motor, a stationary oil receiving device mounted on the motor shaft, a port connected with the oil receiving device, a non-rotatable tubular element fitting over the shaft of the electric motor and having a portion snugly fitting between the motor shaft and the stationary oil receiving device and secured to said stationary oil receiving device, said tubular element having a circumferential recess in communication with the said ports, a plurality of longitudinal ports communicating with the circumferential port for discharging oil into said cup.

2. In an oil burner, in combination, a fan housing, having a rotatable fan therein, an oil discharging cup within the fan housing, said cup and fan being operatively connected with the shaft of an electric motor, a stationary oil receiving device, a port connected with the oil receiving device, a tubular element fitting over the shaft of the electric motor and secured to said stationary oil receiving device, said tubular element having a circumferential recess in communication with the said ports, a plurality of longitudinal ports communicating with the circumferential port for discharging oil into said cup.

nal ports communicating with the circumferential port for discharging oil into the cup, an oil feeding device having spiral grooves located within the cup for feeding the oil discharged within the cup as a film to the outlet of said cup.

3. In an oil burner, the combination with a base for supporting a motor, said base being provided with an integral diaphragm 10 chamber in the lower portion thereof, a diaphragm in said chamber, an extension for said diaphragm, said extension protruding through an opening in the lower wall of said chamber, a fan housing, a rotatable oil atomizing cup within said fan housing, said cup and fan being secured to the shaft of said motor, a communication from said diaphragm chamber to said fan housing, an oil admission conduit in close proximity to said 20 chamber, a valve for said conduit, a lever adjustably secured to said extension for the diaphragm, and pivotally secured with respect to said oil conduit, said lever being provided with an engaging finger at its extremity for engaging said valve to open the same to admit oil to the said atomizing cup when the pressure transmitted from said fan

housing to said diaphragm chamber reaches a predetermined value.

4. In an oil burner, the combination with 30 a base for supporting a motor, said base being provided with a diaphragm chamber in the lower portion thereof, a diaphragm in said chamber, an extension for said diaphragm, said extension protruding through 35 an opening in the lower wall of said chamber, a fan housing, a rotatable oil atomizing cup within said fan housing, said cup and fan being secured to the shaft of said motor, a communication from said diaphragm to 40 the fan housing, an oil admission conduit in close proximity to said chamber, a valve for said conduit, a lever adjustably secured to said extension for said diaphragm, and pivotally secured with respect to said oil conduit, 45 said lever being provided with a portion for engaging said valve to open the same and admit oil to said atomizing cup when the pressure transmitted from the fan housing to the diaphragm chamber reaches 50 a predetermined value.

In testimony whereof I affix my signature.

RICHARD R. EZDORF.
